UNITED STATES PATENT OFFICE.

WILLIAM W. SMITH, OF JERSEY CITY, NEW JERSEY.

BOILER.

Application filed December 15, 1928. Serial No. 680,901.

This invention relates to water tube boilers and aims to provide an improved structure which can be readily erected and one which is comparatively inexpensive to build.

5 Two embodiments of the invention are illustrated in the accompanying drawings in which;

Fig. 1 is a side elevation of the boiler the left side of the figure being broken away to reveal interior parts;

10 Fig. 2 is a transverse vertical section taken on the line 2—2 of Fig. 1;

Fig. 3 is a side elevation showing a modified form of boiler;

15 Fig. 4 is a transverse section on the line 4—4 of Fig. 3;

Fig. 5 is a detailed section on the line 5—5 of Fig. 2;

20 Fig. 6 is an enlarged detail showing one of the plates forming part of the baffle wall.

Figs. 7 and 8 are detail views.

Referring in detail to the drawings the boiler shown in Figs. 1 and 2 includes lower supporting end walls 2 and 4, side walls 6 and 25 8 which enclose a heating chamber 10. This chamber is divided into two compartments 12 and 14 by a central longitudinal wall 16. The wall 16 is provided with a pair of arched openings 18 and 20 and the end wall 4 is provided with an arched opening or port 22 which communicates with a tunnel or flue coming from the regenerator chambers of an open hearth furnace, this boiler being adapted to utilize waste heat from steel furnaces or the like.

30 Located on opposite sides of the heating chamber are lower drums 24 and 26 which are connected by means of a multiplicity of boiler tubes 28 and 30 with a drum or steam header 32 located above the central wall 16.

Steel I-beams 34 and 36 are located on opposite sides of the steam header 32 and carry on their undersides channel beams 38 and 40. Outer boiler shells 42 and 44 are secured at 45 their upper ends to the channels 38 and 40 as shown and at their lower ends to angle plates 46 and 48 as shown. The boiler shells 42 and 44 are formed of separate panels 53 as shown in Fig. 1 and each panel comprises 50 an outer plate 50 and an inner plate 52 between which is located a layer of magnesia 54 or other suitable heat insulating material.

The shells 42 and 44 are arched or bowed as best shown in Fig. 2 and assist in guiding 55 the gases in a circuitous path as will be hereinafter more fully pointed out.

The steam header 32 is partially surrounded by a hood 56 which is supported by side members 58 and 60 carried by the channels 38 and 40. This hood forms an outlet broad enough for the gases to pass through the boiler and is provided with a flanged connection 62 for bolting to a stack connection or the like.

The end walls 64 and 66 are built up of boiler plates and an interposed layer of heat insulating material 65 and a number of doors 68 are provided therein, these doors as shown in Fig. 7 being normally held closed by a releasable locking device 72 pivoted at 70 which, however, is adapted to be disconnected by any suitable means for example by breaking the pin 71 so as to permit the doors 68 to open outwardly in the event that an explosion takes place within the boiler.

Baffle walls 74 and 76 extend transversely 75 across the banks of boiler tubes 28 and 30, these walls meeting arched roofs 78 and 80 supported by the central wall 16. A horizontal plate 82 is connected with angle members 84 and 86 which assist in holding the roofs 78 80 and 80 in position. The plate 82 closes the space between the roofs and forms part of the flue between the banks of tubes.

Baffle plates 88 and 90 are provided at the upper part of the boiler and extend approximately half way across the bank of tubes in a transverse direction as clearly shown. The spaces between the baffle plates 88 and 90 and the side members 58 and 60 respectively are closed by plates 92 and 94 which are secured 90 to the channels 38 and 40.

In the boiler constructed as above described it will be seen that the gases which enter the heating compartment 10 through the inlet port 22, flow to the compartments 12 and 14 95 thence upwardly and outwardly in a direction of the arrows *a* into the spaces enclosed by the arched boiler shells 42 and 44 and thence around the baffles 74 and 76 downwardly and inwardly in the direction of the arrows *b* into the spaces above the plate 82 between the two banks of tubes, thence upwardly and outwardly above the baffles 88 and 90 in the direction of the arrows *c* and finally upward as indicated by arrows *d* on their way to the 105 stack.

The joints in the shell or casing are all of course made air-tight and all joints are preferably closed by interposing a thin strip of asbestos *a* between the overlapping surfaces as shown in Fig. 8. The steam drum or header 32 is provided with suitable man-

holes closed by the usual cover plates 33 secured in place by bolts 35 passing through bridge pieces 37. The water legs are provided with similar manholes which are closed in like manner by covers 25. Suitable clean out doors 27 are provided in the end walls of the boiler and soot blowers 63 are provided which project through the end walls 64 and 66 of the boiler, these providing means whereby the boiler can be periodically cleaned.

The baffle walls above referred to are preferably formed as shown in Figs. 5 and 6. The boiler tubes 28 for example are arranged in staggered relation and the baffle walls are formed of a multiplicity of diagonally disposed malleable iron plates 29 which are provided with a series of notches 31 and 33, the notches 31 on one side of the plate being staggered or offset with respect to the notches 33 on the other side of the plate, the pitch of these notches corresponding to the distance on centers between adjacent boiler tubes in one row. The baffle walls are formed by inserting the plates 29 edgewise between a row of tubes and then turning the plate flatwise. In this way it will be appreciated that the baffles can be readily assembled and that as they burn away they can be readily replaced.

In Figs. 3 and 4 I have shown a slightly modified type of boiler adapted to be heated by fuel introduced into the fire box instead of by the use of waste gases coming from a steel furnace or other source of waste heat.

In this modified form of boiler I provide a suitable fire box 96 enclosed in the masonry walls 98 and roof 100 of the boiler. The end walls 102 of the boiler as shown in Fig. 3 extend upward and terminate at 104 and support a pair of steam headers 106 and 108. The latter are joined by equalizing tubes 110 and 112, the tubes 110 being adapted to permit the free passage of steam from one header to the other and the tubes 112 to permit the passage of water or water and steam from one drum to the other. Water legs 124 and 126 similar to those shown in Fig. 2 are provided with this boiler and these water legs are connected respectively with the headers 106 and 108 by banks of boiler tubes 128 and 130. A side shell 142 lined with fire-brick 143 bridges the space between the water leg 124 and steam header 106 and a similar brick lined side shell 144 bridges the space between the water leg 126 and the steam header 108.

A horizontal wall 182 closes the space between the banks of tubes 128 and 130 and baffle walls 174 and 176 extend outwardly from this wall and compel the gases to travel in a circuitous path as indicated by the ar-

rows in Fig. 4, the gases escaping to the stack through a suitable outlet conduit 156. This boiler is provided with suitable explosion doors such as shown in Fig. 1 and the water legs and the steam headers are provided with manholes and suitable covers therefor. Both types of boilers are provided with the usual water inlet pipes 21 and steam outlet pipes 31 as shown in Fig. 1.

In both forms of boilers illustrated, the outer arched or bowed walls by their shape and location with respect to the water legs, steam header and the baffle walls, assist in so guiding the gases that they do not encounter abrupt obstructions which would interfere with a smooth and uniform continuous flow. Considering one side of the boiler shown in Fig. 2, the gases are first guided across the bank of tubes by the curved roof 74 and baffle wall 78 and said gases strike the curved side shell 42 at such an angle that they tend to curl around and pass inward between the baffle walls 74 and 88. The gases from one side then meet the gases from the other side of the boiler and the stream on each side curls outward and then upward to the stack. In the design of Fig. 4 the curved side shells guide the gases in much the same manner although only one cross baffle wall is here employed and hence the gases take a less sinuous path and it is to be noted in this connection that the boiler tubes are comparatively longer when this design is used.

Though I have described with great particularity the details of the embodiments of the invention illustrated it is not to be construed that I am limited thereto as changes in arrangement and substitution of equivalents may be made by those skilled in the art without departing from the invention as defined in the appended claim.

What I claim is:—

A boiler including in combination a pair of lower drums, a central wall between the latter, a steam header above said central wall, a plurality of banks of tubes connecting said lower drums and said steam header, baffle walls extending transversely of said tubes, roofs extending upwardly and outwardly from said central wall and terminating at said baffle walls, side walls parallel with said central wall terminating adjacent said lower drums, curved side shells forming outer walls opposite said tubes and a casting connected with said side shells enclosing part of said steam header and having a gas outlet formed therein.

In witness whereof, I have hereunto signed my name.

WILLIAM W. SMITH.
